UNITED STATES PATENT OFFICE

160,445

STUFFED TOY ANIMAL FIGURE

Edwin S. Valliant, Medford, Oreg., and Philip K. Sunter, Los Angeles, Calif.

Application November 15, 1949, Serial No. 6,048

Term of patent 14 years

(Cl. D34—2)

To all whom it may concern:

Be it known that we, Edwin S. Valliant, a citizen of the United States, residing at Medford, Oregon, and Philip K. Sunter, a citizen of the United States, residing at West Los Angeles, Calif., have invented a new, original, and ornamental Design for a Stuffed Toy Animal Figure, of which the following is a specification, reference being had to the accompanying drawing, forming part thereof.

We claim:

The ornamental design for a stuffed toy animal figure, as shown.

EDWIN S. VALLIANT.
PHILIP K. SUNTER.
